[57] **CLAIM**

The ornamental design for a combined video monitor and loudspeaker system front panel assembly, substantially as shown and described.

DESCRIPTION

FIG. 1 is a front, top and left side perspective view of a combined video monitor and loudspeaker front panel assembly showing our new design, with the broken line structure being purely environmental and forming no part of the claimed design;

FIG. 2 is a front elevational view thereof;

FIG. 3 is a right side elevational view thereof;

FIG. 4 is a left side elevational view thereof;

FIG. 5 is a top plan view thereof; and

FIG. 6 is a bottom plan view thereof.

FIG. 1

FIG. 2

FIG. 3

FIG. 5

FIG. 4

FIG. 6
